(57) **CLAIM**

The ornamental design for a waterproof sand-proof handbag, as shown and described.

DESCRIPTION

FIG. 1 is a front perspective view of a waterproof sand-proof handbag showing my new design;

FIG. 2 is another front perspective view thereof;

FIG. 3 is a front view thereof;

FIG. 4 is a rear view thereof;

FIG. 5 is a left side view thereof;

FIG. 6 is a top view thereof;

FIG. 7 is a bottom view thereof; and,

FIG. 8 is an enlarged view of circled portion 8 of FIG. 2, thereof.

Any shading and cross-hatching are not features of the design but are utilized to illustrate the surface contours of the waterproof sand-proof handbag case design in the drawings. The dot-dash broken lines depict the boundaries of the FIG. 2 and FIG. 8 enlargement that forms no part of the claimed design.
